**ELECTRICAL CONNECTOR ASSEMBLY
WITH HIGH SPEED DOUBLE DENSITY
CONTACT ARRANGEMENT**

BACKGROUND OF THE INVENTION

1. Field of the Invention

The present invention relates generally to an electrical connector assembly with the high speed module and the sideband module thereof, and particularly to the high speed module equipped with the grounding bar and directly attached to the cable. The instant application relates to another copending application having the same filing date, the same applicant, and the same title.

2. Description of Related Arts

U.S. Pat. No. 10,559,930 discloses an electrical connector having the high speed contacts and the sideband contacts arrangement in two rows. U.S. Pat. No. 10,069,262 discloses an electrical connector with the double density contact arrangement. U.S. provisional application Ser. No. 63/004,068 discloses how to make the high speed contact arrangement via a single contact carrier.

It is desired to have the electrical connector with the combo features of the aforementioned three type connectors.

SUMMARY OF THE INVENTION

To achieve the above object, an electrical connector assembly comprises an insulative housing with a front mating slot and a rear receiving; a combo contact module assembly received within the receiving cavity and including a sideband contact module sandwiched between a pair of high speed contact modules; each high speed contact module including an upper unit and a lower unit assembled with each other in the vertical direction; each of the upper unit and the lower unit including a front subunit and a rear subunit; each of the front subunit and the rear subunit includes differential pair contacts alternately arranged with grounding contacts in a transverse direction; and a metallic grounding bar discrete from the grounding contacts mechanically and electrically connecting to the grounding contacts.

Other advantages and novel features of the invention will become more apparent from the following detailed description of the present embodiment when taken in conjunction with the accompanying drawings.

BRIEF DESCRIPTION OF THE DRAWING

FIG. 23 is a side view of the contacts of the high speed contact module and the corresponding cables of the electrical connector assembly of FIG. 1;

FIG. 24 is a perspective view of the upper unit of the high speed contact module of the electrical connector assembly according to another embodiment of the invention;

FIG. 25 is a further perspective view of the upper unit of the high speed contact module of the electrical connector assembly of FIG. 24;

FIG. 26 is a perspective view of the grounding bar of the high speed contact module of the electrical connector assembly of FIG. 24;

FIG. 27 is an exploded perspective view of the upper unit of the high speed contact module of the electrical connector assembly of FIG. 24;

FIG. 28 is a perspective view of the rear subunit of the upper unit of the high speed contact module of the electrical connector assembly of FIG. 27;

FIG. 29 is a perspective view of the upper unit of the high speed contact module of the electrical connector assembly according to a third embodiment of the invention;

FIG. 30 is an exploded perspective view of the upper unit of the high speed contact module of the electrical connector assembly of FIG. 29;

FIG. 31 is another exploded perspective view of the upper unit of the high speed contact module of the electrical connector assembly of FIG. 30;

FIG. 32 is a further exploded perspective view of the upper unit of the high speed contact module of the electrical connector assembly of FIG. 30; and

FIG. 33 is another exploded perspective view of the upper unit of the high speed contact module of the electrical connector assembly of FIG. 32.

DETAILED DESCRIPTION OF THE PREFERRED EMBODIMENT

Referring to FIGS. 1-23, an electrical connector assembly 100 includes an insulative housing 110 enclosing therein a contact module assembly 120 which includes a sideband contact module 180 sandwiched between a pair of high speed contact modules 122. The housing 110 forms a front mating slot 111 and a rear receiving cavity 112. A plurality of guiding grooves 116 are formed at a rear end of the housing 110 for cooperation with the sideband contact module 180 of the contact module assembly 120, and a plurality of securing apertures 114 are formed in the upper and bottom walls of the housing 110 for cooperation with the high speed contact modules 122 of the contact module assembly 120. A cutout (not labeled) is formed in the bottom wall of the housing 110 for allowing contact tail extension toward the printed circuit board (not shown) on which the housing 110 is mounted.

Each high speed contact module 122 includes an upper unit 130 and a lower unit 130' stacked with each other in the vertical direction wherein the upper unit 130 and the lower unit 130' are structurally similar/identical to each other and arranged in an essentially symmetrical manner in the vertical direction, thus saving the manufacturing cost on the mold designs. In detail, the upper unit 130 and the lower unit 130' are offset from each other with one half of (contact) pitch in the transverse direction as shown in FIGS. 8 and 9. Based upon the similarity and identifiability between the upper unit 130 and the lower unit 130', only the upper unit 130 is described in detail.

The upper unit 130 includes a front/outer contact subunit 160 and a rear/inner contact subunit 170 assembled together as a contact unit 150 by a metallic shell 140. The front/outer contact subunit 160 includes a plurality of contacts 164 integrally formed within a front/outer insulator 162 via insert-molding, and the rear/inner contact subunit 170 includes a plurality of contacts 174 integrally formed with a rear/inner insulator 172 via insert-molding. The contacts 164 includes two pairs of differential pair contacts 166 alternately arranged with three grounding contacts 165 in the transverse direction wherein the tails of the grounding contacts 165 are linked together with a transverse bar (not labeled). The manufacturing of the contacts 164 can be referred to the aforementioned U.S. provisional application Ser. No. 63/004,068.

The front/outer insulator 162 forms a front protrusion 161 and three rear protrusions 163 so as to be received within the front opening 148 and the rear opening 149 of the metallic shell 140. Three deformable posts 169 are formed on the front/outer insulator 162 for cooperation with the grounding bar (300) (illustrated later). A plurality of receiving grooves 167 are formed in an underside of the front/outer insulator

162 for receiving the contacting sections of the corresponding contacts 174 of the rear/inner contact subunit 170.

Correspondingly, the contacts 174 include two pairs of differential pair contacts 176 alternately arranged with three grounding contacts 175 wherein the tails of the grounding contacts 175 are linked together via a transverse bar (not labeled). The rear/inner insulator 172 forms a plurality of front protrusions 173 and a plurality of rear protrusions 179 wherein the front protrusions 173 cooperating with the corresponding rear protrusions 163 to be commonly received within the opening 149 of the shell 140, and the rear edge of the shell 140 abuts against the rear protrusions 179.

Notably, via cooperation of the openings 148, 149 in the shell 140 and the protrusions 161, 163 of the insulator 162, and the protrusions 173 and 179 on the insulator 172, the shell 140 and the insulators 162, 172 are secured to each other in the front-to-back direction. The rear/inner insulator 172 further forms a plurality of side protrusions 171 to be received within the corresponding securing apertures 114, respectively, thus assuring securement between the shell 140 and the insulators 162, 172 in both the vertical direction and the front-to-back direction. As shown in FIG. 16, a plurality of protrusions 177 are formed in an underside of the insulator 172 to be received within a corresponding recess form in the lower unit 130', and a recess 178 is formed in the underside of the insulator 172 to receive the corresponding protrusions extending upwardly from the lower unit 130', thus assuring retention between the upper unit 130 and the lower unit 130' in the front-to-back direction and the transverse direction.

Notably, after assembled, the shell 140 is retained to the insulator 172 via engagement of the protrusions 171 within the corresponding securing apertures 146 with the insulator 162 is sandwiched between the shell 140 and the insulator 172 in the vertical direction. The shell 140 of the upper unit 130 further forms a pair of retention sections 144 to retain to the corresponding retention sections of the shell of the lower unit 130'. In the insulator 162, the three protrusions 163 form a pair of passages (not labeled) therebetween to allow extension of the corresponding cables 200. Similarly, the insulator 172 forms a pair of upper passages 152 in an upper side to receive the corresponding two cables 200 which are linked to the upper unit 160, and a pair of lower passages 152 to receive the two corresponding cables 200 which are linked to the lower unit 170. The shell 140 further includes a securing tang 142 which will be securely retained in the securing aperture 114 when the contact module assembly 120 is assembled into the housing 110.

The cable 200 includes a pair of inner conductors 202, a pair of inner insulative layer 204, a common metallic/shielding braiding layer 206 and a common outer insulative layer (jacket) sequentially arranged with one another. The inner conductor 202 is soldered upon the tail of the differential pair contact 166, the braiding layer 206 is mechanically and electrically connected to the transverse bar of the grounding contacts 165. A grounding bar 300 which is discrete from the grounding contacts 165, includes three holes 302 through which the deformable posts 169 extend for securing the grounding bar 300 on the insulator 162, and three beams 304 respectively contacting the corresponding grounding contacts 165, and two bulged sections 304 each of which may cover the whole exposed insulative layer 204 in the vertical direction for lowing the impedance, compared with the traditional design with the exposed insulative layer 204 while without the grounding bar covering such an exposed insulative layer 204. The grounding bar 300 may

optionally further cover the upper part of a front edge region of the braiding layer 206, if desired.

Notably, in the rear/inner contact subunit 170, the arrangement among the contacts 174 and the insulator 172 and the cable 200 is similar to that in the front/outer contact subunit 160 but in a symmetrical/mirror manner, i.e., in the front/outer contact subunit 160, the braiding layer 206 of the cable 200 being located on an upper side of the corresponding transverse bar of the grounding contacts 165 while that being located on an underside of the corresponding transverse bar of the grounding contacts 175 in the rear/inner contact subunit 170.

Referring to FIGS. 18-22, the sideband contact module 180 includes a plurality of wafers 182 stacked with one another in the transverse direction. Each wafer 182 includes an insulator 184 with a contact set 186 embedded therein via insert-molding. The contact set 186 includes an upper contact unit 187 and a lower contact unit 189 wherein the upper contact unit 187 unitarily forms a pair of contacting arms 196 with respective and spaced front and rear contacting sections in the front-to-back direction, and the lower contact unit 189 unitarily forms a pair of contacting arms 198 with respective and spaced front and rear contacting sections in the front-to-back direction. The upper contact unit 187 further includes a pair of tails 194 spaced from each other in the front-to-back direction. The lower contact unit 189 further includes a pair of tails 192 spaced from each other in the front-to-back direction. Notably, if necessary, the pair of contacting arms 196 can be electrically separated from each other by removing the T-shaped structure (not labeled) located between the corresponding pair of tails 194 because a stamping hole (not labeled) is formed in the insulator 184 to expose such a T-shaped structure. Similarly, the pair of contacting arms 198 can be electrically separated from each other by removing the T-shaped structure (not labeled) located between the corresponding pair of tails 192. In fact, the contacting arms 196 and the contacting arm 198 are not located in a same vertical plane but being offset from each other in the transverse direction. Therefore, the insulator 184 forms a protrusion 183 and a recess 185 on two sides to result in such an offset structure. Such an offset structure also facilitates stacking of the wafers 182 in the transverse direction correctly and stably. Each wafer 182 further forms a protrusion 188 to be received within a corresponding recess formed in the neighboring wafer 182. Each wafer 182 further includes a guiding rib 181 which is received within the corresponding guiding groove 116 when assembled. Notably, the thickness direction of the contact set 186 is the transverse direction while the thickness direction of the contacts 164, 174 is perpendicular to the transverse direction.

Referring to FIGS. 24-28 which show another embodiment same with the first embodiment except the beam 304 of the grounding bar 300 is replaced with the resilient beam 434 of the grounding bar 430 to omit the soldering process between the beam 304 and the corresponding grounding contact 175 in the first embodiment. In other words, in this embodiment, the resilient arm 434 mechanically presses the corresponding grounding contact 450 without soldering while the braiding layer 456 is still requisitely soldered upon the transverse bar (not labeled) of the grounding contacts 450. Understandably, in the second embodiment, all other components keep the same with those of the first invention. The front contact subunit includes a plurality of contacts 336 retained in the insulator 332, and the rear contact subunit 334. The grounding bar 430 is retained to the insulator 332

via the posts 460. The cable 451 is composed of the inner conductor 452, the inner insulative layer 454, the braiding layer 456 and the outer insulative layer 458. Notably, in the invention the grounding bracket 300, 430 is to essentially mostly cover the exposed inner insulative layer 204, 454 in the vertical direction for reducing the impedance thereof. Notably, the housing 110 forms a plurality of passageways (not labeled) beside the mating slot 111 to receive the contacting sections of the corresponding contacts, respectively. Notably, the contact unit 186 are stamped and operably deflected in the direction perpendicular to the thickness direction while the contacts 164, 174 are stamped and formed and operably deflected in the direction compliant with the thickness direction.

Referring to FIGS. 29-33 which show the third embodiment same with the first embodiment except omit the beam 304 of the metallic grounding bar 500. Understandably, in the third embodiment, all other components keep the same with those of the first invention. The front contact subunit 510 includes a plurality of contacts 536 retained in the insulator 532, and the rear contact subunit includes a plurality of contacts 538 retained in the insulator 534. The contacts 536 includes two pairs of differential pair contacts 546 alternately arranged with three grounding contacts 547 in the transverse direction wherein the tails of the grounding contacts 547 are linked together with a transverse bar 540. The contacts 538 includes two pairs of differential pair contacts 548 alternately arranged with three grounding contacts 549 in the transverse direction wherein the tails of the grounding contacts 547 are linked together with a transverse bar 540. In this embodiment, the metallic grounding bar 500 is not retained to the insulator 532 via the posts 460. The grounding bar 500 comprises two bulged sections 504 and three level sections 505. The cable 551 is composed of the inner conductor 552, the inner insulative layer 554, the common metallic shielding layer 556 and the outer insulative layer 558. Each of bulged sections 504 cover the exposed common metallic shielding layer 556 and each of the level section 505 contacted to the corresponding grounding contacts 537. Each of the bulged sections 504 and the level section 505 has holes 510 for solder, through which the metallic grounding bar 500 directly soldered to the transverse bar 540 of the grounding contacts 537 and the common metallic shielding layer 556.

Although the present invention has been described with reference to particular embodiments, it is not to be construed as being limited thereto. Various alterations and modifications can be made to the embodiments without in any way departing from the scope or spirit of the present invention as defined in the appended claims.

What is claimed is:

1. An electrical connector assembly comprising:
an insulative housing with a front mating slot and a rear receiving cavity;
a combo contact module assembly received within the receiving cavity and including a sideband contact module sandwiched between a pair of high speed contact modules in a transverse direction;
each high speed contact module including an upper unit and a lower unit configured to be assembled with each other in a vertical direction perpendicular to the transverse direction;
each of the upper unit and the lower unit including a front subunit and a rear subunit;
each of the front subunit and the rear subunit including differential pair contacts alternately arranged with grounding contacts in said transverse direction; and

a metallic grounding bar discrete from the grounding contacts mechanically and electrically connecting to the grounding contacts of each of the front subunit and the rear subunit; wherein

the high speed contact module is connected to cables while the side band contact module is connected to a printed circuit board on which the housing is seated; the cable comprises a pair of inner conductors, an inner insulative layer, and a common metallic shielding layer, the inner conductors of the cable are mechanically and electrically connected to the differential pair contacts, and the metallic shielding layer of the cable is mechanically and electrically connected to the grounding contacts; and

the metallic grounding bar includes beams respectively contacting the corresponding grounding contacts and bulged sections each of which covers a corresponding cable.

2. The electrical connector assembly as claimed in claim 1, wherein each of the front subunit and the rear subunit includes an insulator with deformable posts, the metallic grounding bar includes holes through which the deformable posts extend for securing the grounding bar on the insulator.

3. The electrical connector assembly as claimed in claim 2, wherein the beams of the metallic grounding bar is soldered to the corresponding grounding contacts.

4. The electrical connector assembly as claimed in claim 2, wherein the beam of the metallic grounding bar is resilient to omit the soldering process between the beam and the corresponding grounding contact.

5. The electrical connector assembly as claimed in claim 1, wherein the metallic grounding bar is directly soldered to grounding contacts and the common metallic shielding layer.

6. The electrical connector assembly as claimed in claim 5, wherein the metallic grounding bar comprises level sections covering the exposed common metallic shielding layer and bulged sections contacting the corresponding grounding contacts, and each of the bulged sections and the level sections has holes for solder.

7. The electrical connector assembly as claimed in claim 1, wherein the sideband contact module includes a plurality of wafers stacked with one another in the transverse direction and each wafer includes an upper contact unit and a lower contact unit embedded within an insulator.

8. The electrical connector assembly as claimed in claim 7, wherein each of the upper contact unit and the lower contact unit includes a front contact subunit and a rear contact subunit unitarily linked together.

9. An electrical connector assembly comprising:
an insulative housing with a front mating slot and a rear receiving cavity;
a combo contact module assembly received within the receiving cavity and including a sideband contact module sandwiched between a pair of high speed contact modules in a transverse direction;
each high speed contact module including an upper unit and a lower unit configured to be assembled with each other in a vertical direction perpendicular to the transverse direction;
each of the upper unit and the lower unit including a front subunit and a rear subunit;
each of the front subunit and the rear subunit including differential pair contacts alternately arranged with grounding contacts in said transverse direction; and

a plurality of cables connected to the differential pair contacts and the grounding contacts, each of the cables including a pair of inner conductors and a metallic braiding layer; wherein

all the grounding contacts of each of the front subunit and the rear subunit are unified together via a transverse bar unitarily linked to corresponding rear ends thereof, and the inner conductors are connected to the signal contact while the braiding layer is connected to the transverse bar; and

each of the front subunit and the rear unit further includes a metallic grounding bar cooperating with the corresponding transverse bar to sandwich the corresponding cables therebetween in the vertical direction, and said grounding bar includes arms respectively contacting the corresponding grounding contacts.

10. The electrical connector as claimed in claim 9, wherein the metallic grounding bar of the front subunit is assembled thereto in a first vertical direction while the metallic grounding bar of the rear subunit is assembled thereto in a second vertical direction opposite to the first vertical direction.

11. An electrical connector assembly comprising:
an insulative housing with a front mating slot and a rear receiving cavity;

a combo contact module assembly received within the receiving cavity and including a sideband contact module sandwiched between a pair of high speed contact modules in a transverse direction;

each high speed contact module including an upper unit and a lower unit configured to be assembled with each other in a vertical direction perpendicular to the transverse direction; and

each of the upper unit and the lower unit including a front subunit and a rear subunit;

each of the front subunit and the rear subunit including a plurality of contacts with tails connecting to corresponding cables; and

the side band contact module including a plurality of terminals having tails configured to connect to a printed circuit board; wherein

a thickness direction of each terminal is the transverse direction while that of each contact is perpendicular to the transverse direction.

12. The electrical connector assembly as claimed in claim 11, wherein the sideband contact module includes a plurality of wafers stacked with one another in the transverse direction, and each wafer includes an upper contact unit and a lower contact unit to form the terminals thereof.

13. The electrical connector assembly as claimed in claim 12, wherein viewed along a front-to-back direction perpendicular to both the transverse direction and the vertical direction, each wafer forms an offset structure so that the upper contact unit and the lower contact unit are offset from each other in the transverse direction.

14. The electrical connector assembly as claimed in claim 13, wherein the front subunit and the rear subunit are configured to be assembled with each other in the vertical direction.

15. An electrical connector assembly comprising:
an insulative housing with a front mating slot and a rear receiving cavity;
a combo contact module assembly received within the receiving cavity and including a sideband contact module sandwiched between a pair of high speed contact modules in a transverse direction;

9

each high speed contact module including an upper unit and a lower unit configured to be assembled with each other in a vertical direction perpendicular to the transverse direction;

each of the upper unit and the lower unit including a front subunit and a rear subunit;

each of the front subunit and the rear subunit including differential pair contacts alternately arranged with grounding contacts in said transverse direction; and a respective metallic grounding bar discrete from the grounding contacts mechanically and electrically connecting to the grounding contacts of each of the front subunit and the rear subunit; wherein the high speed contact module is connected to cables while the side band contact module is connected to a printed circuit board on which the housing is seated; the cable comprises a pair of inner conductors, an inner insulative layer, and a common metallic shielding layer, the inner conductors of the cable are mechanically and electrically connected to the differential pair contacts, and the metallic shielding layer of the cable is mechanically and electrically connected to the grounding contacts; and

each of the front subunit and the rear subunit includes an insulator with deformable posts, the metallic grounding bar includes holes through which the deformable posts extend for securing the grounding bar on the insulator.

16. An electrical connector assembly comprising:

an insulative housing with a front mating slot and a rear receiving cavity;

a combo contact module assembly received within the receiving cavity and including a sideband contact module sandwiched between a pair of high speed contact modules in a transverse direction;

10

each high speed contact module including an upper unit and a lower unit configured to be assembled with each other in a vertical direction perpendicular to the transverse direction;

each of the upper unit and the lower unit including a front subunit and a rear subunit;

each of the front subunit and the rear subunit including differential pair contacts alternately arranged with grounding contacts in said transverse direction; and a respective metallic grounding bar discrete from the grounding contacts mechanically and electrically connecting to the grounding contacts of each of the front subunit and the rear subunit; wherein the high speed contact module is connected to cables while the side band contact module is connected to a printed circuit board on which the housing is seated; the cable comprises a pair of inner conductors, an inner insulative layer, and a common metallic shielding layer, the inner conductors of the cable are mechanically and electrically connected to the differential pair contacts, and the metallic shielding layer of the cable is mechanically and electrically connected to the grounding contacts;

the metallic grounding bar is directly soldered to the grounding contacts and the common metallic shielding layer; and

the metallic grounding bar comprises level sections covering the exposed common metallic shielding layer and bulged sections contacting the corresponding grounding contacts, each of the bulged sections and the level sections has holes for solder.
